UNITED STATES PATENT OFFICE.

CHARLES F. McBEE, OF ATHENS, OHIO.

PAPER-BINDER.

1,374,594.

Specification of Letters Patent. Patented Apr. 12, 1921.

Application filed June 4, 1917. Serial No. 172,677.

To all whom it may concern:

Be it known that I, CHARLES F. McBEE, a citizen of the United States, residing at Athens, in the county of Athens and State 5 of Ohio, have invented a certain new and useful Improvement in Paper-Binders, of which the following is a specification.

My invention relates to that class of devices which permanently bind a number of 10 sheets into volumes.

My invention has for its object to produce a very simple and inexpensive means whereby the user can do his own binding, and also to provide a device which will automatically 15 lock itself in position and one which will be adjustable to various thicknesses of volumes.

My means of accomplishing the foregoing objects may be more readily understood by having reference to the accompanying drawings, which are hereunto annexed and are 20 a part of this specification, in which:

Figure 1 is a view of a volume bound with my invention, part of the leaves being broken away to show the operation of the 25 binder.

Fig. 2 is an enlarged detail view of the device.

Fig. 3 is a cross section of the binder on line 3—3 in Fig. 2.

Similar reference numerals refer to similar parts throughout the entire description.

As shown in the drawings, the leaves forming the volume 3 are punched with holes of the exact diameter of a cross section of my 35 binder which is formed in two parts 4 and 5, each of which is provided with a head 6, and are semi-cylindrical, the flattened portion being provided with a plurality of ratchet teeth 7, which are inclined toward the head, 40 the two parts when the teeth 7 are in engagement, forming a round rod or post.

The operation of the device is as follows:

Having selected the desired number of leaves to be bound into the volume, they are placed so that the holes punched therein, are 45 in register with each other and one part of the binder is inserted from the bottom and the other is started in the same hole from the top, when a few blows of the hammer will drive the post parts in until the head 6 engages the outside of the volume 3. There is sufficient give in the paper to permit the teeth to pass each other, but it also exerts enough pressure to hold them tightly in engagement as shown in Fig. 1 so that they 55 hold the leaves permanently and in fact, they can only be removed by cutting them out. As the ratchet teeth 7, extend from the head to the point, it is apparent that they will hold any thickness intermediate the combined length of the two parts 4 and 5, less the number of teeth required to hold the leaves together. Obviously, different lengths of binders may be provided for large or 60 small volumes.

Having described my invention what I regard as new and desire to secure by Letters Patent is:

In a paper binder, a binder post formed in two longitudinally divided sections having 70 flat abutting axial faces provided with interengaging teeth for holding the post sections together, each section having its inner end formed with a V-terminal and its outer end with a thin headed terminal overhanging the 75 companion section, said post being of uniform diameter throughout the interengagement of said post sections.

In testimony whereof, I have signed the foregoing specification.

CHARLES F. McBEE.
